Primary Examiner — Cathy Anne MacCormac(74) *Attorney, Agent, or Firm* — Mitchell Law PLLC;
Matthew W. Mitchell(57) **CLAIM**

The ornamental design for a pet resting enclosure, as shown and described.

DESCRIPTION

FIG. 1 is a front isometric view of the pet resting enclosure of the present invention;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The use of stippling represents surfaces having the contrast in appearance shown.

1 Claim, 7 Drawing Sheets(56)
